UNITED STATES PATENT OFFICE.

HENRY B. NICHOLS AND GEORGE B. TAYLOR, OF PHILADELPHIA,
PENNSYLVANIA.

DESIGN FOR A RAILROAD-RAIL.

SPECIFICATION forming part of Design No. 30,910, dated May 30, 1899.

Application filed May 3, 1898. Serial No. 715,484. Term of patent 14 years.

To all whom it may concern:

Be it known that we, HENRY B. NICHOLS and GEORGE B. TAYLOR, citizens of the United States, residing at the city of Philadelphia, in the county of Philadelphia and State of Pennsylvania, have invented and produced a new and original Design for Railroad-Rails, of which the following is a specification, reference being had to the accompanying drawings, forming part hereof, in which—

Figure 1 is a perspective view of the rail of our design, and Fig. 2 is a transverse section through the same.

The leading feature of the design of our invention consists of the unitary structure made the subject of illustration and having the shape or configuration hereinafter described.

Referring to the drawings, A represents

the rail in shape or configuration as shown, 20 provided with bases a, a', and a² and recesses or openings b, b', and b², extending into the body of the rail, and the flanges c and c' and end recesses d and d'.

Having thus described our invention, what 25 we claim as new, and desire to secure by Letters Patent, is—

The design for a railroad-rail, substantially as illustrated and herein described.

In testimony whereof we have hereunto 30 set our signatures in the presence of two subscribing witnesses.

HENRY B. NICHOLS.
GEO. B. TAYLOR.

Witnesses:

J. WALTER DOUGLASS,
RICHARD C. MAXWELL.
